DUSTING BRUSH FOR VACUUM CLEANERS

Abram L. Brakman, Rochester, N. Y.

Application October 18, 1945, Serial No. 623,079

2 Claims. (Cl. 15—398)

1

The present invention relates to a brush attachment for vacuum cleaners, designed especially for convenient use in dusting operations. The principal object of the invention is the provision of an improved brush so designed and constructed as to be particularly efficient in the operation of removing dust from furniture, draperies, curtains, etc.

Another object is the provision of a brush so constructed that it may be used with the greatest ease, even by an inexperienced person.

Still another object is the provision of a vacuum dusting brush so constructed as to give a good distribution of vacuum within the space enclosed by the bristles of the brush.

A further object is the provision of a dusting brush in which the bristles are firmly held against accidental loosening, and in which they are so placed that no matter how much downward pressure is applied to the brush, the bristles will not cover or clog the vacuum passageway.

A still further object is the provision of a vacuum dusting brush so constructed that it is easier and more convenient to use than prior brushes.

These and other desirable objects are accomplished by the construction disclosed as an illustrative embodiment of the invention in the following description and in the accompanying drawings forming a part hereof, in which:

Fig. 1 is a side elevation of a dusting brush in accordance with a preferred embodiment of the present invention;

Fig. 2 is a vertical section taken longitudinally through the same;

Fig. 3 is, in part, a horizontal section through the same;

Fig. 4 is a cross section taken substantially on the line 4—4 of Fig. 3; and

Fig. 5 is an enlarged longitudinal section taken substantially on the line 5—5 of Fig. 3, showing the manner of attaching the bristles to the body of the brush.

The same reference numerals throughout the several views indicate the same parts.

The brush of the present invention comprises, in its preferred form, a brush back member 11 formed preferably of molded plastic material and having an elongated shape, slightly dished downwardly except at its ends, as shown in Figs. 2 and 4, and provided with a central longitudinal slot 13 somewhat shorter than the length of the brush but extending throughout the major part of the length, as shown in Figs. 2 and 3. The back member 11 is provided with two rows of inclined holes 15 and 17, larger at the lower ends than at their upper ends, for receiving tufts of brush bristles or hairs 21 and 23 respectively, which tufts are held in place by wire stitching as indicated at 25, formed preferably of fine cop-

2

per wires extending along the top of the brush back 11 and looped downwardly through the holes 15 and 17 to extend through each separate tuft of bristles, as shown. The individual bristles in each tuft are approximately twice the length of the tuft, and are folded or doubled back upon themselves at the upper end of the tuft (seated in the holes 15 and 17) and the wire stitching 25 extends through each tuft of bristles at the center of the bend or fold, so that all of the individual bristles in the tuft are, in effect, wrapped around the wire stitching 25, as shown. Thus the bristles are held very securely in place and will last for an unusually long time without danger of accidental dislodgement. As seen in Fig. 5, the bristles are seated in the larger-diameter lower portions of the holes, and the wires 25 come down to the bristles through the smaller-diameter upper portions of the holes.

20 A cover member 31, likewise preferably of molded plastic material, has a downwardly extending marginal flange 33 all the way around its periphery, tightly embracing the periphery of the member 11. For a short distance inwardly from the marginal flange 33, the bottom of the cover member 31 is flat, and the corresponding top part of the back member 11 (in the vicinity of the wire stitching 25) is likewise flat, and a suitable cement or adhesive 35 (Fig. 4) is interposed 25 between these two flat portions of the cover 31 and back 11, respectively, serving not only to hold the cover on the back, but also to hold the stitching 25 firmly in place and prevent dislodgement of the bristle tufts, even if the stitching should accidentally break. Further inwardly, toward the center of the brush and beyond the area covered by the adhesive 35, the bottom surface of the cover 31 is hollowed as at 37 to increase 30 the size of a chamber formed between the back member and the cover member. This chamber merges gradually into a cylindrical neck portion 41, the axis of which lies in the same vertical plane with the longitudinal center line of the brush, and at an angle of about 45° to the horizontal plane of the brush back. This cylindrical neck 41 is of the proper size to fit the standard hose attachment or extension customarily used in association with vacuum cleaners, and is provided 35 with any suitable device or construction for holding the neck 41 firmly on the end of the hose or extension with which it is to be used.

It is noted from Figs. 3, 4, and 5 that the bristles 21 of the inner row are staggered with respect 40 to the bristles 23 of the outer row, and that these two rows are quite close together, so that the two rows of bristles in conjunction with each other form a substantial wall around the periphery of the brush. It is also noted that the brush 45 is distinctly elongated, the rear end being pref-

erably semicircular and the front end slightly pointed, as shown, and the brush being sufficiently narrow so that it may be thrust easily into small spaces or openings, such as the spaces between sections of a heating radiator. Also it is noted that both rows of bristles 21 and 23 are inclined outwardly at a substantial angle, preferably being inclined at about 10° to 15° from a vertical position, so that if downward pressure is applied to the brush to tend to mash it down onto a surface, the bristles in mashing down will definitely swing outwardly rather than inwardly, and thus will not clog or interfere with the vacuum opening or passageway 13, which will at all times remain open and be capable of carrying off the dust and dirt by means of a current of air flowing through this passageway 13, thence through the hollowed out space between the back and the cover of the brush, and thence to the neck 41 and on to the vacuum apparatus.

The use of the long narrow slot 13 in the back of the brush has been found to be quite advantageous, since it distributes the vacuum approximately evenly throughout the space enclosed by the bristles. If this restricted slot were not employed, and if the brush back 11 were cut away to a substantially larger extent, the vacuum would be largely concentrated in the vicinity where the neck 41 connects with the brush, about two-thirds of the way back from the front end of the brush. There would be a great rush of air in this vicinity, and a great reduction of the suction at the front and rear ends of the brush. But by cutting only a restricted elongated slot 13 through the back 11 of the brush, rather than a larger opening, it is found that all parts of the space enclosed by the bristles are subjected to an adequate amount of vacuum or suction, greatly improving the operation of the brush.

In use, the long narrow body of the brush may be directly grasped by the fingers, or the neck 41 or the hose extension connected to this neck can be grasped. In either event, the use of the brush is very easy. It may be moved up and down along draperies or curtains hanging on a window, and the bristles will dislodge loose dust from the draperies or curtains while the suction will immediately pick up the dislodged dust and carry it away. Due to the great length of the brush (preferably about ten or twelve inches) a wide streak of cleaning is accomplished by each lateral stroke of the brush, so that a large area is quickly cleaned, yet in spite of this great length of the brush, it is not heavy or awkward in use, because of its narrowness. The fact that the hose connection is in the same vertical plane with the longitudinal axis of the brush makes this brush much easier to use in getting into restricted openings or passageways in furniture, radiators, etc., than the conventional vacuum brushes in which the handle or hose connection is approximately at right angles to the longitudinal axis of the brush. The great usefulness of the present brush is easily demonstrated by a few moments of actual use. Yet along with all these advantages, the brush is extremely simple and inexpensive to manufacture.

It is seen from the foregoing disclosure that a construction is provided which admirably fulfills the above-mentioned objects of the invention. It is to be understood that the foregoing disclosure is given by way of illustrative example

only, rather than by way of limitation, and that without departing from the invention, the construction may be varied within the scope of the appended claims.

5 What is claimed is:

1. A vacuum dusting brush comprising a relatively long and narrow brush back member having two rows of bristles projecting obliquely downwardly and outwardly from the lower face of said back member continuously around all sides of said member, said bristles being relatively long and flexible; a slot formed through the thickness of said brush back member and extending longitudinally thereof approximately centrally thereof throughout the major part of the length of said back member; a cover member overlying said back member; said cover member having a depending marginal flange around its periphery embracing and covering the lateral edge of said back member substantially completely around the perimeter thereof, the lower face of said cover member being spaced upwardly from the upper face of said back member throughout the central part of said member, and a tubular vacuum connection neck formed integrally with said cover member and rising obliquely therefrom at a point intermediate the ends of said cover member; said tubular neck having an axis lying approximately in the same vertical plane as the longitudinal axis of said back member and cover member and being inclined at an angle of approximately 45 degrees to said longitudinal axis.

2. A vacuum dusting brush comprising a relatively long and narrow brush back member rounded at its rear end and pointed at its forward end, a plurality of closely adjacent rows of relatively long and flexible bristles projecting obliquely downwardly and outwardly from the lower face of said back member close to the perimeter thereof and continuously around all sides of said perimeter; a long narrow slot extending through said back member approximately along the center line thereof through substantially more than half of the length thereof, a cover member overlying said back member and having a depending marginal flange embracing and covering the lateral edge of said back member around substantially the complete perimeter thereof, the central part of said cover member having its lower face spaced upwardly from the upper face of said back member, and a tubular vacuum connection neck formed integrally with said cover member and extending obliquely upwardly and rearwardly therefrom at an acute angle at a point approximately two-thirds of the distance from the forward end of the brush toward the rear end thereof.
